UNITED STATES PATENT OFFICE

LÉON RIBÉ, OF ST.-ETIENNE, FRANCE

SUPERPOSED BARREL, BREECH-LOADING FIREARM

Application filed April 2, 1931, Serial No. 527,245, and in France April 5, 1930.

My invention relates to double barrelled, breech loading firearms, of the drop-down type, wherein the barrels are superposed, that is arranged one above the other.

5 It has for its object to provide an efficient percussion mechanism, simple in construction and readily attached to the breech. This mechanism is provided with hammers axially disposed with respect to the guns, 10 an arrangement which is in contradiction with what has been hitherto proposed in firearms of this type.

In the annexed drawings:

Fig. 1 is a side view of a percussion 15 mechanism according to my invention, the cover being supposedly removed.

Fig. 2 is a side view of the opposed side with respect to Fig. 1.

Fig. 3 is an end view of the mechanism.

20 Fig. 4 is a partial plan view of the breech.

Fig. 5 is a side view of the same portion.

Fig. 6 is a bottom plan view of the same.

Fig. 7 is an end view of the same.

25 Fig. 8 is a side view of the tail piece of the breech.

Fig. 9 is a plan view of the same.

Fig. 10 is a bottom plan view of the sliding bolt with its driving arm.

30 Fig. 11 is a section of a modification comprising two separate sliding bolts.

Fig. 12 is a plan view of the same.

Fig. 13 is a general side view of the gun at the closed position, the wood parts sup- 35 posedly removed.

Fig. 14 is a similar view at the opened position.

The percussion mechanism, Figs. 1 to 3, 40 comprises a central frame 1 closed by two side covers 2 and 2'. The hammers are in the form of rectilinear rods 4 and 4' provided with heads 5 and 5' which support the striking pins, respectively 6 and 6'. These hammers, as shown, are guided with-

45 in frame 1 parallel to each other, with their

axes in a plane lying midway between the axes of the barrels. The actuating springs 7 and 7' of relatively great length are disposed around rods 4 and 4'; they act by pushing the heads 5 and 5', which heads 50 represent the heavier part of the hammers and strike by inertia as a hammer proper does.

It will be readily grasped that the arrangement is symmetrical with respect to 55 an axis located midway of the barrel axes, that is, also midway of the rod axes. The strength of the percussion is equal for both guns. There is no oblique part, difficult to manufacture and liable to cause undue friction and wear.

The frame, as described, also supports the two loading levers 8 and 8' pivoted at 9 and 9' respectively and acting directly on heads 5 and 5'. Levers 8 and 8' are actuated by 60 intermediate levers 10 and 10' pivoted at 11 and 11' and which receive the action of the loading rods 12 and 12'. The latter form no part of this invention and it will only be stated that they are disposed so as 65 to be actuated when the breech is opened. 13 and 13' are light springs provided to maintain in permanent contact the teeth 14—15 and 14'—15' which connect levers 70 8—10 and 8'—10' respectively.

Frame 1 also supports the levers 16 and 16', pivoted at 17 and 17' and provided with the catches 18 and 18' adapted to maintain the hammers at the loaded position. These catches act in a depression 19 or 19' 80 provided in the lower part of heads 5 or 5'. 85

The mechanism as described possesses this advantage that the parts are the same for both strokes. It will readily be grasped that the parts referenced 4, 5, 6, etc. . . . 85 are the same as those referenced 4', 5', 6', etc. . . . save for the depressions 19 and 19' in heads 5 or 5', a matter practically negligible.

It must also be pointed that the contact- 90

ing faces of the cooperating parts (for instance, teeth 14—15 or 14'—15') are easily machined with a true gear tooth profile, which is also a material advantage.

- 5 The parts associated with one hammer are quite independent from those associated with the other. The mechanism described may function separately from the arm, which permits easily adjusting its parts.
- 10 This mechanism, with its covers, is adapted to be fixed to the breech in a particular manner. The breech (Figs. 4 to 7) has no tail portion (contrary to the known arrangements) and it terminates at the rear 15 by a vertical way 20 (Fig. 5) into which the mechanism is upwardly slid as shown in Figs. 13 and 14. The upper face of frame 1 is provided with a projecting part 21, square in horizontal section, which fits 20 into a square hole 22 (Figs. 4, 5 and 6) provided in the breech at the upper end of way 20.

The fixation is perfected in two ways:

- 25 The trigger-guard 23 fits into a depression 24 in the lower face of the breech, where it is fixed by screws 25 (Fig. 13) screwed into holes 26 (Fig. 6). This trigger-guard is also fixed to the frame 1 of the mechanism by screws 27 (Fig. 13) and it is provided with an upwardly projecting portion 28 which fits at the rear of a downwardly projecting part 29 provided on frame 1, as it is clearly understood from Fig. 14.

- 30 A separate tail portion 30 (Figs. 8 and 9) is fixed to the breech by screws 31 (Figs. 13 and 14), screwed into holes 32 of the breech (Fig. 4), and this portion is also fixed to the frame 1 of the mechanism by a screw 33.

- 40 It will be readily understood that by such a fixation, the breech, mechanism, tail portion and trigger-guard form a rigid block as if it were made in one piece.

- A very material advantage of such an arrangement is that the rear portion of the breech is easily machined, without having to forge it.

- 45 Of course, the arrangement described requires a bolt or other barrel locking device, wholly exterior to the breech or percussion mechanism.

- The bolt illustrated comprises a part sliding on the upper face of the breech. The latter (Fig. 7) is provided with a T-shaped 50 projection 34 cooperating with a correspondingly T-shaped sliding bolt 35 (Figs. 10, 13 and 14) which, when pushed towards the barrels, projects over the same and locks them in position. This bolt is loaded by springs 60 (Fig. 14) acting on fingers 37 depending from the same, said springs and fingers being housed into ways 38 provided in the breech (Fig. 7). It is actuated by a lever 39 (Fig. 10) pivoted at 40 on the bolt itself 65 and provided with a radial slit 41 cooperat-

70 ing with a pin (not shown) fixed into a hole 43 of the breech (Fig. 4). When lever 39 is rotated in the direction of arrow 44 (Fig. 10), the bolt is pulled toward the rear and frees the barrels.

75 A device is provided whereby the bolt is retained in its rear position (position of Fig. 14) when the barrels are dropped, to avoid the rear face of the same striking and rubbing against the front face of the bolt when the breech is again closed. This device comprises a small spring loaded piston 45 (Fig. 14), housed in a vertical blind hole 46 of the breech (Figs. 4 and 14) and terminating upwardly into a tooth 47 by which bolt 35 is retained, as shown in Fig. 14. When the breech is closed, a lateral projection 48 fixed to the barrels (or integral with the same) strikes tooth 47 and lowers piston 45, whereby bolt 35 is freed and closes under the action of springs 36 (Fig. 13).

80 Figs. 11 and 12 illustrate a modification in which two bolts are used. These bolts 49 and 49' are disposed laterally of the breech and each is loaded by a spring 36. 85 The actuating lever 50 is pivoted at 51 on the breech and it acts directly on bolt 49. This lever 50 also actuates an intermediate lever 52 pivoted at 53 on the breech, and which in turn actuates bolt 49'. Of course, 90 with this modification, it is necessary to provide two retaining pistons 45, one on each side of the barrels.

I claim:

1. In a double-barrelled, drop-down, 95 breech-loading firearm, a frame having a vertical median partition in the vertical plane of the barrels, and a percussion device on each side of the partition and symmetrically positioned with respect thereto, each 100 percussion device comprising a rectilinearly movable hammer, a spring bearing on the hammer, striking means acting directly on the primer and rigidly connected to the head of the hammer, and means carried by the 105 frame for retaining and releasing the hammer.

2. The device set forth in claim 1, in which the head of the hammer has a large mass with respect to the other portions of the 110 hammer.

3. The device set forth in claim 1, in which the striking means is fixed substantially at the center of gravity of the head of the hammer.

4. The device set forth in claim 1, in which the spring bearing on the hammer, the head of the hammer, and the striking means are symmetrically positioned with respect to an axis in the plane of the axes of the barrels, parallel to the axes of the barrels and equidistant therefrom.

5. The device set forth in claim 1, including means for locking the barrels to the breech, said means comprising a bolt slid-

able on the breech, a finger depending from the bolt, a spring positioned in a groove in the breech and acting on the depending finger, and an operating lever pivoted on the bolt and acting on a portion of the breech.

5 6. The device set forth in claim 1, in which the hammer has a long travel and is acted on by a long and strong spring.

7. The device set forth in claim 1, including a tail portion fixed to the breech and a trigger guard, the percussion device being movable in the breech, the fixation of the percussion device being obtained by the trigger guard and tail portion.

15 15 In testimony thereof I affix my signature.

LÉON RIBE.
